J. Q. SHERMAN

MANIFOLDING MACHINE

Filed Sept. 19, 1921

INVENTOR:

John D. Sherman

BY

Allen & Allen

ATTORNEYS.

UNITED STATES PATENT OFFICE.

JOHN Q. SHERMAN, OF DAYTON, OHIO.

MANIFOLDING MACHINE.

Application filed September 19, 1921. Serial No. 501,601.

To all whom it may concern:

Be it known that I, JOHN Q. SHERMAN, a citizen of the United States, and a resident of Dayton, in the county of Montgomery and State of Ohio, have invented certain new and useful Improvements in Manifolding Machines, of which the following is a full, clear, and exact description, reference being had to the accompanying drawings, forming part of this specification.

My invention relates to manifolding machines wherein the object is to feed a plurality of webs over a writing table or platen in sections of adjustable length.

In former applications for patent, viz:— Serial No. 433,208 and Serial No. 436,774, filed Dec. 27, 1920, and Jan. 12, 1921. I have described various devices for the purpose of frictionally feeding paper webs in lengths which are optionally controlled by varying the arc of contact of the friction feeding members. Also in application filed by me Serial No. 443,009, filed February 7, 1921, I have described a method of feed of manifolding paper by means of radially moving pins, which are thrust into holes in the paper by cam devices of fixed position and adjustable length.

In the patent to Schirmer No. 940,481, dated November 16, 1909, is shown and described the so-called "pin wheel" method of paper feed wherein wheels carrying radial pins are used to feed and align a number of webs of paper with marginal holes therein, said webs being held loosely in the machine while the feed is going on so as to permit self-adjustment of the webs.

My present invention involves a different principle from those set forth in the first set of applications above referred to, in that it relates to pin wheel methods of feed of paper, one of the modifications relating to the radially moving pin structure, secondly above referred to.

The object of the present invention is to provide a device by means of which adjustable length strips can be fed but in which the true alignment feed of the Schirmer type is adhered to. The adjustable devices having arcs of controllable length are used to enforce a separation of the pins from the holes in the paper.

The structure shown varies in nature, but has in common the pin wheel feed and the

adjustable working periphery devices which 55 effect the said separation.

I accomplish my object by that certain construction and arrangement of parts to be hereinafter more specifically pointed out and claimed.

In the drawings,

Figure 1 is a side elevation showing one form of adjustable pin wheel feed, in which the entire pin wheel devices are thrust downwardly away from the paper.

Figure 2 is a side elevational detail of a radial moving pin feeding device, in which the pin operating cam devices are thrust downwardly, so as not to thrust the pins into paper engagement.

Figure 3 is a side elevation of a still simpler form in which the adjustment operates on the writing table itself to lift the paper from the pins.

Figure 4 is a detail elevation of the feed 75 inhibiting device of Figure 3 shown at right angles to the showing in said former figure.

Figure 5 is a view of the feed inhibiting devices of Figure 1 in edgewise elevation.

Figure 6 is a detail of the paper guiding 80 roll common to all of the modifications.

I indicate at 1 the side frames of all of the modifications, and at 2 the main writing table portion over which the webs of paper are to pass. I also indicate by a common reference numeral the main feed shafts 3 in all views, and the paper guide rollers 4. This construction is that of the Schirmer patent referred to, except for the particular mounting of the feed shafts. The adjustable members for each modification are the same also and comprise segment-shaped plates having journals on the feed shaft.

Thus in each case there is a fixed segment plate 5 having its collar 6 pinned to the feed shaft. There is also another segment plate 7 having a like periphery journaled loosely over the feed shaft alongside of the first named plate. These segment devices are like those shown in my applications, Serial 95 No. 433,208 and No. 436,774.

The loosely journaled plate being free to revolve may be positioned alongside of the fixed plate, so that but a short arc is represented by the combined peripheries, but it may be moved into other positions radially of the feed shaft to form desired extensions of the arc of the fixed piece. In order to

retain the movable plate in adjusted position a pin 8 is set into its face, which pin passes through an arcuate slot 9 in the fixed plate. The pin has a threaded end on which is a suitable clamp nut 10.

In Figures 2 and 3 the upper or guide roller 4 is mounted as in the Schirmer patent, above referred to, with springs above the spindles of the rolls to hold them down in proper position of abutment on contact wheels 11 mounted on the feed shafts.

In Figure 1 the roller 4 is mounted between a pair of arms 12 on a cross rod 13 set into the machine frame and spring-energized at 14. The arms 12 or one of them has a nose 15 at the end which may be engaged by a latch 16 to hold the roller upwardly and out of the way when installing paper in the machine. The arms 12 may also carry a tear-off knife when desired.

In the simplest form of device, as shown in Figure 3, the writing table is hinged at 17 in any usual manner familiar in the manifolding machine art, and carries on its underside directly over the feed shaft and in line with the segment device a roller 18 in a simple bracket 19. Where the segment plate devices are duplicated the rollers may be duplicated, but a single adjustable segment device and one roller will suffice to accomplish my purpose.

The feed of the paper is accomplished by one or more pin wheels 20 on the feed shaft. The pins 21 on these wheels pass through slots in the writing table and engage successive holes in the paper. The contact wheels 11 extend through slots in the table also.

When the segment device comes into contact with the roller 18, it lifts the writing table and thus forces it upwardly so as to strip the paper off the pins and the guide roller off the cams.

The guide roller will then be clamped tightly against the writing table and the paper held against any movement until the table is dropped again, whereupon the next pin of the pin wheel to come into juxtaposition with the paper web holes will pick up the feeding where it left off.

In this construction it will be a simple matter to arrange the timing of the initial lifting motion and the duration of the lift together with the movement of the pins, so that the paper will come down again over the pins which have moved around and come to a stop in about the exact position in which it was lifted. It will be noted that the handle of the feed shaft will come to the end of its motion and be latched, as is common practice in manifolding machines, at just the point where the lifting action of the segment devices comes to an end.

Referring next to Figure 1, it will be observed that the feed shaft is mounted on a

housing or journal box 30, at each end, these boxes being set into slideways 31 on the side frames.

The journal boxes are pressed upwardly by springs 32 mounted beneath them as shown and the pin wheels 20 on the shaft, as well as the cams or contact wheels 11 for the guide roller 4, are held up into operating position by means of the springs. At their uppermost positions the journal blocks come into contact with stops 33.

The segment or segments in this instance contact with a roller or rollers 34 on a cross bar 35 set beneath the writing table, and force the entire feed shaft down, so as to withdraw the pin wheels and permit the guide roller to come down and clamp the paper.

In the showing in Figure 2 additional reference being hereby made to my application, Serial No. 443,009 the pins 40 are carried in a set of wheels having outer rims 41 in which the pins slide, and inner rims 42 serving as a spring abutment and through which the reduced ends 43 of the pins will slide. The pins have springs 44 thereon, which are secured to the ends thereof and bear against this inner rim. A pair of cams 45 are provided and mounted on resiliently supported pieces 46, which are set into slideways 47. The slideways are supported by rods 48 in the sides of the machine.

When held up normally by the springs 48 these pieces 46 hold the cams in position to contact with the ends of the pins and force them radially into a position of engagement with holes in the paper. When forced down against the spring action the pieces remove the cams, so that the pins do not rise into engagement but are kept out of same by the springs thereon.

The segments in this instance contact with rollers set on a cross bar 49 connecting the two pieces 46.

It will be noted that all the modifications have the same common features of a pin feed and an adjustable inhibiting device which effects a separation of the pins and the paper.

The last described modification might be better operated with a clamp to engage the paper when the pins are out of engagement, but as I have shown such a clamp in my co-pending application Serial No. 452,185, filed March 14, 1921, I do not believe it to be necessary to go into further details in this case, particularly as in the claims that follow I do not specifically claim this one of the modifications.

I do not desire it to be presumed that my invention is intended to be limited to the three modifications shown, because of the fact that I have not mentioned others.

Having thus described my invention, what

I claim as new and desire to secure by Letters Patent, is:—

1. In a manifolding machine, a pin wheel feed for paper strips, and means operating in conjunction with the said feeding means for removing the pins and paper from operative juxtaposition, said means being adjustable for duration of operation during portions of single cycles of operation of the pin wheel feed. 70
2. In a manifolding machine, a pin wheel feed for paper strips, an element having a periphery of adjustable extent movable with the feed, and serving as a cam, and means lying in the path of the cam and adapted when in contact therewith to effect a removal of the pins and paper from operative juxtaposition. 89
3. In a manifolding machine, the combination with a paper support over which a plurality of webs of paper are to be fed, rotary means having pins thereon passing through clearance in said support to engage successive holes in the said paper, and means for enforcing a separation between the support and the rotary means, for the purpose described. 85
4. In a manifolding machine, the combination with a paper support over which a plurality of webs of paper are to be fed, rotary means having pins thereon passing through clearance in said support to engage successive holes in the said paper, and means for enforcing a separation between the support and the rotary means, for the purpose described, said means being operable automatically from the operation of the rotary means. 95
5. In a manifolding machine, the combination with a paper support over which a plurality of webs of paper are to be fed, rotary means having pins thereon passing through clearance in said support to engage successive holes in the said paper, and means for enforcing a separation between the support and the rotary means, for the purpose described, said means being operable automatically from the operation of the rotary means and having an adjustable component to extend the duration of the separation during cycles of movement of the rotary means. 105
6. In a manifolding machine, the combination with a paper support over which a plurality of webs of paper are to be fed, rotary means having pins thereon passing through clearance in said support to engage successive holes in the said paper, and means for enforcing a separation between the support and the rotary means, for the purpose described, said means being operable automatically from the operation of the rotary means, and comprising segmental cam devices on a common center and adjustable to extend or diminish the combined operative peripheries thereof. 115
7. In a manifolding machine, a feeding device for webs of paper, comprising movable pins adapted to engage holes in the paper and feed it in the desired direction, and automatically operated means in connection with the feeding device for effecting a separation of the pins and the paper. 120
8. In a manifolding machine, a feeding device for webs of paper, comprising movable pins adapted to engage holes in the paper and feed it in the desired directions, and automatically operated means in connection with the feeding device for effecting a separation of the pins and the paper, said last noted means being adjustable for duration of the said separation for individual cycles of operation of the feeding device. 125
9. In a manifolding machine, the combination with a paper support over which webs of paper are to be drawn, a series of pins adapted to engage holes in the paper and draw it over the support, means for imparting motion to said pins and means for effecting a depression of the pins so that all pins are out of contact with the paper, during a portion of the actuation of the motion-imparting means above noted. 90
10. In a manifolding machine, the combination with a paper support over which webs of paper are to be drawn, a series of pins adapted to engage holes in the paper and draw it over the support, means for imparting motion to said pins and means for effecting a depression of the pins out of contact with the paper, said means being adapted to operate during operation of the motion-imparting means above noted, said means comprising a rotary segmental cam device and a stop against which said device contacts, said cam being mounted on the motion imparting means. 100
11. In a manifolding machine, a paper support, a feed shaft beneath it, rotary pin bearing bodies on the shaft adapted to engage holes in the paper through clearance in the support, a contact member on the shaft, an abutment member against which it contacts, said member being adapted when in contact position to depress the feed shaft. 110
12. In a manifolding machine, a paper support, a feed shaft beneath it, rotary pin bearing bodies on the shaft adapted to engage holes in the paper through clearance in the support, a contact member on the shaft, an abutment member against which it contacts, said member being adapted when in contact position to depress the feed shaft, and comprising a plurality of segmental pieces arranged on the shaft, and adjustable with relation to each other to control the working periphery made up of the several pieces. 120
13. In a manifolding machine, a paper support, a feed shaft beneath it, rotary pin 130

- bearing bodies on the shaft adapted to engage holes in the paper through clearance in the support, a contact member on the shaft, an abutment member against which it contacts, said member being adapted when in contact position to depress the feed shaft, and comprising a plurality of segmental pieces arranged on the shaft, and adjustable with relation to each other to control the working periphery made up of the several pieces, one of said pieces being fixed and the other movable, and means for locking the pieces to each other in desired adjusted relation.
14. In a manifolding machine, a pin wheel feed for paper strips, and means operable in connection with the said feeding means for removing the pins and paper from operative juxtaposition, and a tension member adapted to clamp the paper during said removal from juxtaposition.
15. In a manifolding machine, a pin wheel feed for paper strips, and means operable in connection with the said feeding
- means for removing the pins and paper from operative juxtaposition, said means being adjustable for duration of operation during cycles of operation of the pin wheel feed, and a tension member adapted to clamp the paper during said removal from juxtaposition.
16. In a manifolding machine, the combination with a paper support over which a plurality of webs of paper are to be fed, rotary means passing through clearance in said support to engage successive holes in the said paper, and means for enforcing a separation between the support and the rotary means, for the purpose described, said means being operable automatically from the operation of the rotary means.
17. In a manifolding machine, a rotary feed for paper strips, a support over which the paper passes, and means for moving the support and the rotary feed apart for a portion of the complete cycle of the rotary feed.

JOHN Q. SHERMAN.
